DUAL JACKETED ENGINE PROVIDED WITH DUPLEX COOLING SYSTEMS

Lucius D. Watkins, Milwaukee, Wis., assignor to Outboard Marine & Manufacturing Company, Waukegan, Ill., a corporation of Delaware

Application January 5, 1949, Serial No. 69,313

14 Claims. (Cl. 121—41.47)

1

This invention relates to a dual-jacketed engine provided with duplex cooling systems in which the respective jackets are connected. The invention has particular utility in, and will be described in connection with, an outboard motor, since it is a feature of the invention that different head resistances are established for the respective cooling systems by discharging coolant therefrom at different levels. Thus, in its preferred embodiment, the invention has particular application to outboard motor practice in which the coolant is discharged, instead of being recirculated. It is, however, possible to provide other means for varying the head resistance in the respective systems and, even in a closed system, it is possible to discharge the coolant to the atmosphere at different levels.

A great deal of study has been devoted to the problem of cooling an outboard motor engine. The amount of water which is pumped through the cooling system at high engine speeds, and is required to prevent overheating at such speeds, will over-cool the cylinder at low engine speeds, causing carbon deposits. Outboard motors are peculiarly subject to these problems because they are commonly used in fishing and are also used in transportation. In transportation service, they generally operate at wide open throttle for substantial periods of time whereas, in fishing, the engine is ordinarily operated as slowly as it will function.

It is further desired to supply variable amounts of cooling water according to the speed of the engine and to accomplish this result without mechanically operative parts, since the heavy use to which outboard motors are subjected precludes the use of any delicate parts which might be damaged, and the failure of which might cause expensive injury to the engine. Therefore, completely automatic operation without the addition of any moving parts is an important objective of the invention.

More specifically, it is the object of the invention to provide a duplex cooling system with two separate jackets, each of which has its own water supply and return lines, the cold water being admitted to the respective jackets at opposite sides of the cylinder block for increased uniformity of cooling effect during high speed operation. One of the jackets does not function at all at low speed operation, when the heat developed is at a minimum, this desirably being the jacket closest to the cylinder head where combustion occurs.

In the drawings:

Fig. 1 is a view partially in side elevation but

2

largely in vertical fore and aft section through an outboard motor embodying the invention.

Fig. 2 is a diagrammatic view of the duplex cooling system.

5 The outboard motor will not be described in detail, since the present invention is concerned only with the cooling of the cylinder block 3 of power head 5. As usual, the power head is mounted at the upper end of the shaft housing 6 which serves as a strut connecting the power head with the so-called lower unit 7. For purposes of illustration, I have shown an engine having two cylinders at 8 and 9 with spark plugs at 10. The pistons are connected to a crank 15 shaft 11 which drives the aligned drive shaft 12, whereby power is communicated to the propeller 13.

The lower unit 7 provides at least one pump. As illustrated, there is a single pump chamber 20 in which there is a centrifugal impeller 15 mounted on the vertical drive shaft 12. The lower unit has inlets at 16 from which the water passes through port 17 into the pump casing. The water leaves the casing through a delivery port 18 located near the periphery of the casing and passes upwardly through a conduit 19 from which the separate pipes 20 and 21 lead to the respective jackets 22 and 23.

Any desired type of jacket may be used. For convenience of illustration, I have shown jackets which constitute extensions of the respective pipes, the extensions 22 and 23 being molded or cast directly into the cylinder block 3. It will be observed that the jacket extension 22 of pipe 20 passes about the cylinders 9 and 8 in a clockwise direction, while the jacket extension 23 of pipe 21 passes about the cylinders counterclockwise. As explained in the statement of objects, this is done so that, when considerable heat is being developed at high engine speeds, the coldest water, as it arrives from the pump, cools both of the opposite sides of the cylinder block alike, or nearly so.

From the jacket extension 22 of pipe 20, there is a return line 24 which ends at or near water level, this being indicated by the line marked W. L. in both views of the drawing. From the jacket extension 23 of pipe 21, there is a return line 25 which ends, preferably in the exhaust conduit 26, well above the water line. The water delivered from pipe 25 passes with the exhaust gases downwardly to the exhaust outlet 21.

When an outboard motor is first started, it almost invariably operates at full speed, drawing water from the body of water in which it moves and delivering such water under pressure of the

pump 14, 15 through the duplex cooling system to the respective jackets. There is considerably greater head resistance to the continued flow of water through the cooling system supplied by duct 21 than through the cooling system supplied by duct 20, due to the fact that the return duct 24 of the latter cooling system extends so much closer to (or below) water level, that the weight of water on the return side of the system nearly or completely balances the weight of the water in the supply side of the system so that the only energy required to maintain circulation in this system is the energy required to overcome friction therein. In the case of the system which includes supply pipe 21, jacket 23 and return pipe 25, the head is greater because the return pipe is materially shorter than the supply pipe so that the weight of water on the return side of the system is not as great as that in the supply side, thereby creating a differential head which must constantly be overcome if water is to flow through this secondary system.

As long as the engine is operated at high speed, the pressure developed at the pump will be more than adequate to insure flow through both the primary and the secondary cooling systems. However, when the motor is throttled, as for use in trolling, the pressure developed at the pump is no longer adequate to supply both systems, and, due to the greater head in the secondary system, and the continued siphonic action in the primary system, duct 20 will get the water in preference to duct 21 and there will be little or no flow through the jacket portions of the secondary cooling system. The jacket in the secondary cooling system is desirably located closest to the closed ends of the cylinders wherein the spark plugs are located, it being desirable to maintain a predetermined minimum temperature in the combustion chamber to avoid carbon deposits at low speed.

I claim:

1. The combination with an engine operable at varying speeds and pump means driven therefrom at varying rates according to said engine speed, said engine being provided with a cylinder, of two separate jackets for said cylinder, primary and secondary cooling systems leading from said pump means to the respective jackets, said systems including coolant discharge pipes at differing levels, the said jackets being spaced axially of the cylinder and the jacket closest to the combustion end of said cylinder being connected in the system having its discharge at the higher level.

2. The device of claim 1 in which the respective jackets have supply and discharge connections such as to require coolant to pass circuitously about the cylinder, the said connections being reversed as between the respective systems.

3. In an outboard motor having an engine, a strut and a lower unit, portions of said outboard motor, including said lower unit, being adapted to operate submerged during the use of a motor and being provided with a water inlet, a shaft extending longitudinally of the strut, a pump in the lower unit driven by said shaft and adapted to receive water through said inlet, a plurality of separate cooling systems supplied by said pump for cooling said engine, the engine having at least one cylinder provided with separate jackets connected into said systems, the said systems including separate return ducts leading from said jackets, one of which ducts terminates at a lower level than the other.

4. The device of claim 3 in which the duct which terminates at the lower level has its discharge end substantially at the level of the water in which the outboard motor operates, the discharge end of the other duct being materially above water level.

5. The device of claim 3 in which the said systems are so connected to the separate jackets that the water flows in opposite directions about said jackets.

6. The device of claim 5 in which the jacket having its discharge duct at the higher level is the jacket nearest the combustion chamber of the engine cylinder.

15 7. In an outboard motor having an engine, a strut and a lower unit, portions of said outboard motor, including said lower unit, being adapted to operate submerged during the use of a motor and being provided with a water inlet, a shaft extending longitudinally of the strut, a pump in the lower unit driven by said shaft and adapted to receive water through said inlet, a plurality of separate cooling systems supplied by said pump for cooling said engine, the engine

25 having a plurality of cylinders at least two of which extend horizontally, one above the other, in a common cylinder block provided with separate jackets extending about the block in substantially vertical planes spaced longitudinally of said cylinders from the heads thereof, the said jackets being connected separately into the respective systems and the said systems including separate return ducts leading from said jackets, one of which terminates at a lower level than the other whereby the system in which said other return duct is located offers a greater head resistance to flow from the pump than the system having a return duct terminating at the lower level.

30 8. The device of claim 7 in which the respective jackets and return ducts comprise continuously open tubes embedded in said cylinder block and extending circuitously about the respective cylinders.

45 9. The device of claim 8 in which said tubes extend in opposite directions whereby to cool both sides of the block substantially equally when both systems are in operation.

50 10. The device of claim 9 in which a system connected to the jacket nearest the heads of said cylinders is the system having its return duct terminating at a higher level.

55 11. The combination with an internal combustion engine having a cylinder, of separate primary and secondary cooling jackets for coolant therefor, and a single pump power connected to said engine and provided with branch coolant conduit connections to pass coolant to said jackets in further combination with separate coolant connection systems leading to and from the respective jackets, said connections having differing resistance to coolant flow whereby to establish a differential head resistance as between the separate systems and favor passage of coolant for one of said jackets whereby both jackets pass coolant fluid under high pump pressure but only said one jacket passes coolant fluid under low pump pressure.

60 12. The combination with an internal combustion engine having means for operation thereof at different speeds and having an engine cylinder provided with primary and secondary cooling jackets for coolant flow therein, the secondary jackets being located closer to the combustion end of the cylinder, of a coolant pump

75

and coolant supply connections for said jackets, coolant connection for the secondary jacket being constructed to provide greater resistance to coolant flow, said coolant pump being power connected to the engine for operation at a speed to provide coolant head in accord with the speed of operation of the engine whereby the force of coolant flow differs respectively in said jackets at different engine speeds.

13. The combination of claim 12 in which the greater resistance to coolant flow for said secondary jacket substantially prevents coolant flow therein at predetermined minimum engine speed.

14. The combination of claim 13 wherein the connections for coolant to both jackets are of substantially equal capacity and substantially equally unobstructed, the connection for the secondary jacket having a discharge free and unobstructed at a higher level than the connection for the primary jacket whereby the head resistance of the secondary jacket and its coolant connections is greater than the head resistance of

the primary jacket and its coolant connections and the circulation of coolant from said pump to the primary jacket is favored at low engine speed.
